UNITED STATES PATENT OFFICE.

FERNAND E. D'HUMY, OF ENGLEWOOD, NEW JERSEY.

ELECTRIC-LIGHT FIXTURE.

1,326,393.

Specification of Letters Patent. Patented Dec. 30, 1919.

Application filed February 24, 1919. Serial No. 278,979.

To all whom it may concern:

Be it known that I, FERNAND E. D'HUMY, a citizen of the United States, and resident of Englewood, county of Bergen, and State 5 of New Jersey, have invented certain new and useful Improvements in Electric-Light Fixtures, of which the following is a specification.

This invention relates to lighting fixtures 10 and particularly to electric lighting fixtures designed to change the component rays of an electric lamp into the same relative proportions of rays of various color values as found in daylight.

15 The light emitted by the ordinary electric lamp does not contain the seven colors of the spectrum in the same proportions as the rays of the sun or day light, but contains a preponderance of yellow, orange and red rays.

20 Various methods have been proposed for eliminating these excess rays but none have been satisfactory, owing to the fact that the color value of the light emitted thereby cannot be varied to conform to changes in the 25 spectrum values of daylight under varying conditions. The spectrum values of daylight vary with the time of day, the season of the year, with the locality, and with the condition of the weather. Furthermore, the

30 light from an electric lamp is affected by other nearby sources of light, by the decorative scheme of the adjacent premises, and by variations in current voltage and the condition of the lamp filament. It is the object 35 of the present invention to provide a lighting fixture designed to permit the relative proportions of the component rays of the spectrum to be varied at will so that the light emitted may be caused to simulate day-

40 light under the varying conditions above set forth.

In the drawings, Figure 1 is a vertical sectional view of a lighting fixture embodying the invention;

45 Fig. 2 a fragmentary horizontal section on the line II—II of Fig. 1;

Fig. 3 a bottom view, partly in horizontal section; and

Fig. 4 an enlarged vertical sectional view 50 on the line IV—IV of Fig. 1.

Referring to the various parts by numerals, 1 designates an incandescent electric lamp of ordinary construction supported in a suitable socket in the lamp casing. The 55 lamp casing comprises a parabolical reflecting portion 2 and an enlarged rectangular

portion 3 preferably formed integrally with the reflector 2 and formed with an inwardly extending flange 4 at its outer edge supporting a diffusing or mixing lens 5. The lens 60 or ray-mixing plate 5 is preferably formed of a sheet of plain white glass having its outer surface covered with small prisms 5^a, but any other suitable or known form of diffusing or refracting device may be employed.

A pair of bars or ledges 6 are fixed to opposite sides of the rectangular portion 3 of the lamp casing, in which are journaled the pivot pins 7 and 8 of the end supports 9 and 10 of two series of colored glass plates 11 and 12. A rock arm 13 is formed on each of the plate supports 9 at one side of the lamp casing adjacent the pivot pin of said support, and each support 10 at the same side 75 of the casing is formed with a rock arm 14 adjacent its pivot pin. All of the arms 13 are pivotally connected at their outer ends to a bar or rod 15 extending along the inner sides of said arms and through an aperture 80 16 in the casing, and all of the arms 14 are pivotally connected at their outer ends to a bar or rod 17 extending along the outer sides of said arms and out through the aperture 16. The outer end of bar 17 is pivotally connected to a handle or lever 18 fixed on a shaft 19 journaled in supports 20 formed on a bracket 21 held to one side of the portion 3 of the casing adjacent aperture 16. A pinion 22 fixed on shaft 19 meshes with a pinion 23 85 fixed on a shaft 24 journaled in supports 20. A rock arm 25 fixed on shaft 24 is pivotally connected at its outer end with the outer end of bar 15. By rocking handle 18 the glass plates 11 and 12 may be simultaneously 90 swung in opposite directions. Suitable friction washers 26 and 27 are provided for frictionally holding the parts in adjusted position.

The glass plates are properly colored and 100 treated to give them the desired light-ray absorbing or screening quality, all of the plates of both series being the same color. It will be obvious that while I have shown one ray-absorbing screen, any desired number of screens may be mounted in the casing one above the other, the glass plates or shiftable sections of the different screens being of different colors. The glass sections of the screen may be simultaneously shifted by 110 manipulating the handle 18 so as to form one continuous screen through which all the

rays from the lamp pass before reaching the diffusing lens, or the plates may be adjusted to vertical positions to permit the rays to pass to the diffusing lens without passing through the colored glass plates; or said plates may be adjusted to any intermediate position so that a part of the light flux will pass through the plates and a part between the plates. It will thus be seen that any desired proportion of the excess rays may be filtered out and that the fixture is readily adjustable to vary the proportion of the rays filtered out.

An important feature of the invention resides in the arrangement of the screening plates in two series and the means for shifting the plates of the two series in opposite directions. This arrangement avoids the lateral deflection of the major portion of the rays in one direction when the plates are in partly open position, which would result if a screen were employed made up of sections opening in the same direction. The deflection of rays in opposite directions secured by this arrangement also tends to mix the screened light with the unscreened light passing between the partly opened sections of the screen, thus avoiding the formation of zones of light in the field of illumination having different spectrum values. The ray mixing plate or lens 5 having its outer surface covered with small prismatic projections serves to completely mix the screened and unscreened rays, as the multiplicity of small prisms will bend the light rays in all directions as they pass through the plate. A highly diffused light flux having a uniform spectrum throughout its field is thus obtained.

40. What I claim is:

1. A lighting fixture comprising a source of light, a reflector for projecting the light rays, a sectional translucent ray-filtering device supported in the path of the rays projected by the reflector, and means for shifting the sections of said device relatively to each other to adapt the device to filter any desired proportion of the light rays projected by said reflector.

45. 2. A lighting fixture comprising a source of light, a reflector for projecting the light rays, a diffusing lens, a plurality of colored glass plates interposed between the reflector and lens, and means for shifting said plates relatively to each other to adapt the plates to intercept various proportions of the rays passing from the reflector to the diffusing lens.

50. 3. A lighting fixture comprising a casing having a reflecting surface therein, a source of light in said casing, a diffusing lens mounted in the casing, a series of colored glass plates extending across the casing between the reflector and lens and adapted 55 when in the same plane to intercept all the

rays projected by the reflector, means for pivotally supporting said plates at their ends, and means for swinging said plates about their pivots to permit rays of light to pass between adjacent plates.

70. 4. An illuminating device comprising a source of light, a reflector for projecting the rays emitted by the source of light, a series of colored translucent plates pivotally supported in the path of the projected rays 75 and forming a sectional ray-filtering device, and means whereby certain of said plates may be rocked in one direction and the other plates rocked in the opposite direction about their pivots to and from parallel positions in which said series of plates extends across the path of all of the projected rays.

80. 5. An illuminating device comprising a source of light, a reflector for projecting the rays emitted by the source of light, a series of colored translucent plates pivotally supported in the path of the projected rays, means whereby certain of said plates may be rocked in one direction and the other plates rocked in the opposite direction about their pivots, and a refracting device supported at the opposite side of said plates from the source of light.

85. 6. An illuminating device comprising a source of light, a reflector for projecting the light rays, a glass refracting plate having a surface formed with a multiplicity of small prisms, a plurality of colored glass plates interposed between the reflector and the refracting plate, and means for shifting said plates relatively to each other to adapt the plates to intercept various proportions of the rays passing from the reflector to the refracting plate.

90. 7. An illuminating device comprising a source of light, a reflector for projecting the light rays, two series of colored glass plates, means for pivotally supporting said plates individually at spaced points in the same plane in the path of the projected rays, and means for simultaneously rocking the two series of plates in opposite directions about their pivots to and from positions in the same plane.

95. 8. An illuminating device comprising a source of light, a reflector for projecting the light rays, two series of colored glass plates, means for pivotally supporting said plates individually at spaced points in the same plane in the path of the projected rays, 100 means for simultaneously rocking the two series of plates in opposite directions about their pivots to and from positions in the same plane, and means for holding the plates in their adjusted positions.

105. 9. The combination of a source of light, means for absorbing rays emitted thereby having a certain color value, means whereby said ray-absorbing means may be adjusted to modify the spectrum of any desired 110

125

130

proportion of the light flux, and means for mixing the modified and unmodified portions of the light flux.

10. The combination of a source of light, 5 colored translucent means adjustable to filter various proportions of the light flux, and means for mixing the rays composing the filtered and unfiltered portions of the flux.
- 10 11. The combination of a source of light, a ray-mixing lens having an irregular surface, a ray-filtering device interposed be-

tween the source of light and said mixing lens having a plurality of pivoted colored translucent sections, means for rocking said 15 sections about their pivots simultaneously in different directions to and from parallel positions to vary the proportion of the total light flux filtered by said device, and means for maintaining said sections in their ad- 20 justed positions.

In testimony whereof I hereunto affix my signature.

FERNAND E. D'HUMY.
